(57) **CLAIM**

The ornamental design for a pot irrigation device body as shown and described.

DESCRIPTION

FIG. 1 is a perspective view of the pot irrigation device body;

FIG. 2 is a left side elevational view of the pot irrigation device body;

FIG. 3 is a right side elevational view of the pot irrigation device body;

FIG. 4 is a top plan view of the pot irrigation device body;

FIG. 5 is a bottom plan view of the pot irrigation device body;

FIG. 6 is a back elevational view of the pot irrigation device body; and,

FIG. 7 is a front elevational view of the pot irrigation device body.

The broken lines in the drawings depict portions of the pot irrigation device body that form no part of the claimed design.

1 Claim, 5 Drawing Sheets
